UNITED STATES PATENT OFFICE.

FRANCESCO FERRARA, OF BOSTON, MASSACHUSETTS.

ADJUSTABLE WINDOW-SHADE ROLL AND HOLDER THEREFOR.

1,005,184.

Specification of Letters Patent. Patented Oct. 10, 1911.

Application filed January 27, 1909. Serial No. 474,401.

To all whom it may concern:

Be it known that I, FRANCESCO FERRARA, a citizen of the United States, residing at Boston, in the county of Suffolk and State 5 of Massachusetts, have invented new and useful Improvements in Adjustable Window-Shade Rolls and Holders Therefor, of which the following is a specification.

This invention relates to an improved 10 means for supporting the ordinary spring-actuated window shade roll, consisting of two separate holders, one of said holders being adapted to be attached to the journal pin which is fast to the window shade roll, 15 the other of said holders being adapted to be attached to and detached from the spindle to which the spring which rotates the roll is attached. Each of these holders is adapted to be attached to its respective cord 20 and, preferably, one cord is attached to its holder at a point outside the vertical plane in which the median axial line of said roll is located.

The holders are very small, light and perform 25 every function which is necessary in order that the curtain shall be unrolled from its roll or rolled thereupon, and also said holders render it possible, by means of said cords, to raise and lower the roll, with the curtain thereon, bodily, so that the curtain may be used to cover any desired portion of the upper or lower window sash, or both of 30 said sashes, thus making it possible to open the window at the top or at the bottom, or both top and bottom, and still have the curtain cover that portion of the sashes located 35 between the open spaces.

The invention consists in the combination and arrangement of parts set forth in the 40 following specification and particularly pointed out in the claims thereof.

Referring to the drawings: Figure 1 is a front elevation of my improved curtain roll and holders therefor, the same being shown 45 suspended on cords and in connection with a window sash and casing. Fig. 2 is an end elevation of the holder in which the journal pin is rotated taken from the left of Fig. 1. Fig. 3 is a sectional elevation taken on line 50 3—3 of Fig. 2. Fig. 4 is a sectional elevation taken on line 4—4 of Fig. 3. Fig. 5 is an end elevation of the holder in which the spring spindle is mounted, as viewed from the right of Fig. 1. Fig. 6 is a sectional elevation taken on line 6—6 of Fig. 5. Fig. 7 55 is a sectional elevation taken on line 7—7 of

Fig. 6. In Figs. 3 and 6 a portion of the window shade roll is shown in connection with the respective holders, the same being broken away to save space in the drawings. 60

Like numerals refer to like parts throughout the several views of the drawings.

In the drawings, 10 is a window casing, 11 a window sash, 12 a window shade roll, 13 a window shade fast thereto. 65

14 is the journal pin holder, 15 the spindle holder, 16 and 17 are cords fastened, respectively, to the journal pin holder and the spindle holder, and extending therefrom upwardly over guides 18 and 19, respectively, 70 thence over a guide 20 fast to the window casing, and from said guide 20 extending downwardly to a suitable hook or bracket 21 to which they may be fastened.

The roll 12 has fastened to its left hand 75 end a journal pin 22 which has a flange 23 thereon.

The holder 14 consists of a preferably cylindrical casing wall 24 having a back piece 25 with an arm 26 thereon which terminates 80 at its free end in a finger-piece 27. Preferably the back piece 25 and arm 26 are formed in one piece which constitutes a U-shaped arm, the back piece 25 constituting one leg thereof and the arm 26 constituting the 85 other leg thereof. The outer end of the pin 22 is journaled in a substantially cylindrical hole 29 in the arm 26. The back piece 25 is slotted at 28 to receive that portion of the pin 22 between the flange 23 and the roll 12. 90 The slot 28 is made larger at its upper end than at its lower end, in order that the flange 23 upon the pin 22 may pass therethrough and then said pin drop downwardly in the holder until the shank thereof rests 95 in the smaller lower end of said slot 28.

The cord 16 extends through a hole 30 in the cylindrical wall 24 of the holder 14, and this hole 30 is preferably located in the vertical median axial plane of the roll 12, as 100 will be seen in Figs. 2 and 4.

To attach the holder 14 to the journal pin 22, the pin 22 and the flange 23 are pushed through the slot 28, in the larger part thereof, and then drop down into the position shown in Figs. 3 and 4. At this time, the arm 26 is sprung outwardly into the position shown in dotted lines (Fig. 3). After the pin has been dropped into the lower portion of the slot 28, the arm 26 springs 110 into the position shown in full lines (Fig. 3) with the outer end of the pin 22 extending

through the hole 29 which forms a journal bearing for said pin.

To remove the holder 14 from the roll 12, the reverse of the operation hereinbefore described is followed, the arm 26 first being sprung outwardly, by means of the finger-piece 27, from the position shown in full lines (Fig. 3) to that shown in dotted lines, and the roll then disconnected from the holder by moving the pin upwardly in the slot 28 until the flange is in alignment with the enlarged upper end of said slot, when the same can be moved therethrough and the holder 14 thus disconnected from the 15 roll.

The curtain roll 12 is actuated in the usual manner by a spiral spring 31 which is contained within a recess extending longitudinally of the roll 12 and is fastened at one 20 end thereof to the roll and at the other end thereof to a spindle 32 which extends longitudinally of the roll 12 and beyond the right hand end thereof (Fig. 1). Said spindle is flattened on opposite sides at its outer end 25 at 33, 33 in the usual manner and is provided with longitudinal recesses 34, 34 which are adapted to be engaged by pawls 35, 35 pivoted to the roll 12 and adapted to drop into said recesses 34 and prevent the rotation of the roll relatively to the spindle.

The holder 15 consists, preferably, of a split ring 36 which has an arm 37 extending inwardly therefrom and provided with a slot 38 into which the flattened end of the 35 spindle 32 projects. Said split ring has also two arms 39 and 40 formed on or secured thereto at diametrically opposite points, the arm 39 being provided with a projection or tooth 41 and the arm 40 being provided 40 with a projection or tooth 42, see Fig. 7. These projections 41 and 42 project into the recesses 34 as seen in Fig. 7 and thus prevent the holder from becoming detached from the spindle by movement longitudinally thereon 45 since the recesses 34 are provided with shoulders at their outer ends. The arm 39 is provided with a slot 39' and the arm 40 is provided with a slot 40', see Fig. 7, and through these slots the spindle 32 projects.

50 The cord 17 is attached to the holder 15 by being knotted at one end thereof and passing through a hole 43, said hole being located outside the vertical plane in which the median line of the roll 12 is located. As 55 shown in Figs. 5 and 7, the curtain being suspended by means of the cord 17, attached to the holder 15 at a point located at one side of the vertical plane extending through the median axial line of the roll 12, it will be 60 seen that the weight of the window shade and the pull thereon, when said window shade is pulled downwardly, is counteracted or counterbalanced by this manner of supporting the holder on the cord outside said 65 plane.

To attach the holder 15 to the spindle 32, the opposite sides of the split ring are pressed toward each other, thus moving the projections 41 and 42 away from each other to a sufficient distance to allow the spindle 70 32 to be inserted therebetween, while the flattened end of said spindle projects into the slot 38 in the arm 37. The sides of the split ring are then released and the resiliency of said split ring causes the projections 75 41 and 42 to move toward each other and into their respective recesses 34 in the spindle 32. The holder is then locked to the spindle so that it cannot become detached therefrom by moving longitudinally 80 thereof, and said spindle is prevented from rotating relatively to the holder by the flattened portion which projects into the slot 38 in the arm 37 fast to and forming a portion of said holder.

85 To remove the holder 15 from the spindle and from the roll, the sides of the split ring are pressed toward each other until the projections 41 and 42 pass out of the recesses 34 and the holder 15 is then free to be moved 90 longitudinally of the spindle and thus detached therefrom.

The general operation of the device hereinbefore specifically described is as follows: Having attached the holders 14 and 15 to 95 the roll, as hereinbefore described, the cords 16 and 17 being attached to the holders 14 and 15, respectively, and carried through the guides shown in Fig. 1, the curtain roll and its shade, together with the holders 14 and 100 15, are raised by pulling downwardly upon the cords 16 and 17 at the right of the casing 10. Said roll and the parts carried thereon are lowered by releasing the cords 16 and 17 at the right of the window casing 105 10. When the roll has been raised or lowered to the desired location, the same is held in position by winding the ends of the cords 16 and 17 around the bracket or hook 21. The shade 13 is unrolled from the roll or rolled 110 thereupon in the usual well known manner. If desired, one of the cords 16 or 17 may be released while the other cord is held stationary, and this will result in dropping the window shade roll to a vertical position at 115 one side or the other of the casing, thus removing the roll entirely from in front of the window panes.

Having thus described my invention, what I claim and desire by Letters Patent to secure is:

1. A window shade roll, a pin fast thereto projecting from one end thereof, a holder in which said pin is rotatably mounted, a spindle projecting from the other end of said 125 roll and provided with recesses, a spring, one end fast to said roll, the other to said spindle, pawls mounted on said roll adapted to engage said recesses, a second holder in which said spindle is mounted and provided 130

- with a slot, projections on said second holder adapted to project into said recesses, said spindle being flattened at its outer end and adapted to project into said slot in said 5 second holder, whereby said spindle is prevented from rotating, two cords fast to said holders, and guides over which said cords are adapted to extend, whereby said window shade roll may be raised and lowered.
- 10 2. In combination, a window shade roll, a holder on which one end of said roll is rotatably supported, a spindle projecting from the other end of said roll and having a flattened portion, and a second holder having 15 means interengaging with said spindle adjacent to said flattened portion to lock said second holder to said spindle, said second holder having other means resiliently mounted thereon to yield longitudinally of 20 said spindle and engaging said flattened portion.
3. A spring-actuated window shade roll, a pin fast thereto and projecting from one end thereof, and a holder provided with a 25 slot through which said pin projects and being provided with a substantially cylindrical hole, the outer end of said pin being journaled in said hole.
4. A spring-actuated window shade roll, 30 a pin fast thereto and projecting from one end thereof, a flange on said pin, and a holder provided with a slot through which the portion of said pin between one end of said roll and said flange projects, said 35 holder being also provided with a substantially cylindrical hole, the outer end of said pin journaled in said hole.
5. A spring-actuated window shade roll, 40 a pin fast thereto and projecting from one end thereof, and a holder provided with a slot through which said pin projects and having an arm in which the outer end of said pin is journaled, said pin having a shoulder larger than that portion of said 45 slot in which said pin is journaled.
6. A spring-actuated window shade roll, 50 a pin fast thereto and projecting from one end thereof, a holder provided with a slot through which said pin projects, said holder comprising a U-shaped arm, one of the legs of said U having a slot therein through which said pin projects, the other end of said pin journaled in the other leg of said U-shaped arm, said pin having a shoulder 55 larger than that portion of said slot in which said pin is journaled.
7. A window shade roll, a spindle projecting from one end thereof, said spindle having a flattened end and being provided with 60 a recess, a spring, one end attached to said roll, the other to said spindle, means adapted to lock said spindle against rotation relatively to said roll, a holder provided with a slot through which said flattened end of said 65 spindle is adapted to project, said holder in- cluding yielding means on said holder adapted to engage said recess in said spindle, whereby said holder is prevented from becoming detached therefrom.
8. A window shade roll, a spindle projecting from one end thereof, said spindle having a flattened end and being provided with a recess, a spring, one end attached to said roll, the other to said spindle, means adapted to lock said spindle against rotation relatively to said roll, a holder provided with a slot through which said flattened end of said spindle is adapted to project, said holder being provided with yielding projections on said holder adapted to project into 70 said recesses in said spindle, respectively whereby said holder is prevented from becoming detached from said spindle.
9. A window shade roll, a spindle projecting from one end thereof having a flattened end and provided with a recess, a 75 spring, one end attached to said roll, the other to said spindle, means to lock said spindle to said roll, a holder consisting of a split ring with an arm thereon provided with a slot through which the flattened end of said spindle is adapted to project, and another arm with a projection thereon adapted to project into said recess.
10. A window shade roll, a spindle projecting from one end thereof, said spindle having a flattened end and being provided with recesses, a spring, one end attached to said roll, the other to said spindle, means to lock said spindle to said roll, a holder provided with a slot through which said flattened end of said spindle is adapted to project, and two other arms, each having a projection thereon adapted to project into one 90 of said recesses respectively.
11. A window shade roll, a spindle projecting from one end thereof, said spindle having a flattened end and being provided with recesses, a spring, one end attached to said roll, the other to said spindle, means to lock said spindle to said roll, a holder provided with a slot through which said flattened end of said spindle is adapted to project, and two arms, each having a projection thereon adapted to project into one 95 of said recesses respectively, said arms being provided with slots through which said spindle is adapted to project.
12. In combination, a spring-actuated 100 window shade roll, a pin fast thereto and projecting from one end thereof, and a holder provided with a slot through which said pin projects and being provided also with a hole, the outer end of said pin being journaled in said hole, said pin having a shoulder larger than that portion of said 105 slot which is in alignment with said hole and located between said slot and said hole.
13. In combination, a spring-actuated 110 window shade roll, a pin fast thereto and

projecting from one end thereof, a flange on
said pin, and a holder provided with a slot
through which a portion of said pin between
one end of said roll and said flange projects,
5 said holder being also provided with a hole,
the outer end of said pin being journaled in
and substantially fitting said hole.

In testimony whereof I have hereunto set
my hand in presence of two subscribing wit-
nesses.

FRANCESCO FERRARA.
